UNITED STATES PATENT OFFICE.

STEVE NOVAK, OF EAST ST. LOUIS, ILLINOIS.

GRAIN SAVER FOR BINDERS.

Application filed November 14, 1922. Serial No. 600,990.

To all whom it may concern:

Be it known that I, STEVE NOVAK, a citizen of the United States, residing at 2710 McCasland Avenue, East St. Louis, in the county of St. Clair and State of Illinois, have invented certain new and useful Improvements in Grain Savers for Binders, of which the following is a specification.

This invention relates to grain saving devices for harvesters and binders.

The invention has for its object to produce a device of simple, inexpensive and compact construction which may be readily applied to and used in connection with grain binding harvesters of various well known types for rendering the platform conveyor and straw elevator thereof more efficient in operation.

A further object of the invention is to provide a grain saving device, by means of which the grain straw is properly delivered onto the binder table or deck and prevented from passing from the machine between the straw elevator and said binder table or deck.

With the above general objects in view, and others that will become apparent as the nature of the invention is better understood, the same consists in the novel form, combination, and arrangement of parts hereininafter more fully described, shown in the accompanying drawings, and claimed.

In the drawings, wherein like reference characters indicate corresponding parts throughout the several views:

Figure 1 is an enlarged transverse sectional view, through a portion of a grain binder showing my improved grain saver applied thereto.

Figure 2 is a transverse vertical sectional view upon the line 2—2 of Figure 1, and looking in the direction of the arrows.

Figure 3 is a top plan view of a skeleton frame with a removable cover positioned thereon adapted for application between the two elevator canvases of a binder.

Figure 4 is a perspective view of a skeleton frame per se.

Figure 5 is a top plan view of another skeleton frame with a removable cover positioned thereon, which frame together with the cover is adapted for positioning beneath the platform canvas and the lower elevator canvas of the binder.

Figure 6 is a perspective view of the skeleton frame per se.

Figure 7 is an enlarged perspective view

of one of the connecting links employed between the binder and one end of the skeleton frame shown in Figures 3 and 4, and

Figure 8 is an enlarged fragmentary plan view of a portion of the fabric cover for the skeleton frame shown in Figures 5 and 6.

The frame F of the harvester and binder is supported on the usual bull and grain wheels (not shown) in the usual and well known manner.

The outer end portion of the frame F supports the usual grain platform 1 and the platform apron 2 is guided over rollers R and R' and is equipped with the usual transverse slats that are so arranged or proportioned that in operation they will move over the platform 1.

The usual harvester and binder embodies a straw elevator including a lower conveyor composed of an endless belt or apron 3 which is guided over rollers R² and R³ and which is equipped with slats S', said usual straw elevator further embodying an upper conveyor that includes rollers R⁴ and R⁵ over which is guided another endless apron 4 which is not used or is discarded in the use of the present invention. These two conveyors forming the usual straw elevator serve in a well known manner to carry the cut straw between the aprons thereof from the platform conveyor to the binder deck or table, it being noted that the conveyors of the straw elevator are arranged between a pair of side frame plates disposed upon and rigid with the frame F and in which the ends of the shafts of the rollers R², R³, R⁴, and R⁵, are journaled, the frame plates being rigidly connected at the upper ends of the straw elevator conveyors by means of rods or shafts A or C respectively disposed beneath the rollers R³ and R⁵, and between these last mentioned rollers and the binder deck. The construction thus far described is conventional and well known in the art, and in operation has been found to be defective and to result in the loss of considerable grain straw as the latter is moved from the cutting mechanism to the binder deck or table. The loss of the grain straw principally occurred by passing downwardly between the upper end of the lower straw elevator conveyor and the binder deck or table. Considerable loss of grain was also experienced through the action of the upper conveyor of the straw elevator at the upper end of the latter by reason of the fact that

the endless apron of said upper conveyor and the slats carried thereby travelling at relatively great speed caused the straw to be projected upwardly in a scattered condition 5 so as to not properly fall onto the binder deck or table. Furthermore, considerable of the grain straw would find its way between the lower conveyor of the straw elevator and the binder table or deck downwardly be- 10neath the lower straw elevator. As will hereinafter be pointed out and clearly de- 15scribed, the present invention embraces means for preventing passage of the grain straw between the straw elevator and the binder deck or table and for guiding the same in a positive manner onto the latter.

I arrange a skeleton frame member 5 above the usual lower conveyor of the straw elevator and below the usual upper conveyor 20 thereof, the endless belt or apron of said upper straw elevator conveyor being rendered inoperative or preferably removed in accordance with the present invention. The frame 5 includes a plurality of spaced longitudinal rods 7 having the upper ends thereof downturned as indicated at 8 for directing the elevated grain downwardly onto the binder deck or table and preventing the same from flying upwardly in the objectionable manner above mentioned with respect 30 to the usual upper conveyor apron that I eliminate, the downturned ends 8 of the rods resting upon the rod or shaft A for support. The frame 5 has its lower end 35 supported through the medium of links 13 attached by bolts 15 that extend through openings 14 in said links to the binder brace bar or rod B that overhangs the lower end of the straw elevator and has its lower end 40 rigidly attached to the frame F at the rear edge of the platform 1 as shown in Figure 2. The upturned lower end portions 9 of the frame rods 7 are connected by a transverse rod 10 and prevent the grain from climbing 45 onto the upper surface of said frame 5 and effectively direct the grain from the platform conveyor onto the lower straw elevator conveyor beneath said frame 5. A canvas covered wire frame indicated at 11, 50 12, is disposed upon and suitably secured to the frame 5 for preventing passage of the grain straw upwardly through the frame 5 so that such straw is effectively compressed 55 or held in compact arrangement for being acted upon by the elevating lower conveyor of the straw elevator.

Another skeleton frame 6 is disposed and suitably fixed beneath the lower straw elevator conveyor and the platform conveyor, and the lower horizontal portion of this frame 6 is held spaced above the platform 60 1 by any suitable means. As shown in Figure 2, the frame 6 is disposed between the front and rear members of the machine frame F, so that the same is held in place

against movement transversely of the conveyor belt or apron 2 and this frame 6 may be secured to the frame F in any desired manner to prevent displacement of the same in the direction of travel of the belt 70 2. The frame 6 consists of a plurality of longitudinal bars 18, whose upper ends are downturned as indicated at 19 to extend across the space between the binder deck or table and the upper end of the conveyor 75 including the apron 3 whereby the grain straw will be prevented from passing or falling through the space between the said conveyor and said deck or table and will be also effectively directed onto the table 80 or deck. The ends 19 rest upon the transverse rod or shaft C for support at this point and disposed upon the frame 6 is a canvas covered wire frame as at 21, said cover 21 extending the length of the platform 85 1 and then upwardly beneath the conveyor belt 3 so as to provide floors for the platform and the lower straw elevating conveyor. The cover 21 provides means for catching any grain that is loosened from 90 the straw and conveying the same to a point above the platform 6, onto which said loosened grain may fall by providing perforations or eyelets in the lower horizontal portion of the cover 21 as indicated at 22. 95

It will thus be seen that I have provided effective means for preventing loss of grain straw and grain in its passage from the cutting mechanism to the binder deck, and wherein such straw is effectively directed 100 onto the binder deck as well as prevented from passing between the lower conveyor of the straw elevator and the binder deck and from flying upwardly in passing from said elevator conveyor. 105

As indicated generally at 28 in Figure 2, the cutting apparatus may be mounted in the usual manner on the front of the platform and customary well known means are to be provided for driving the platform and straw elevating conveyors. The rods 18 of the frame 6 may be rigidly connected by cross bars 20 as shown in Figure 6. The lower ends of the links 13 are formed with curved portions 16 which cooperate with 110 clamp plates 17 for securing said links to the cross rod 10 of the frame 5. 115

The improved grain saving and elevating device is simple in construction, easily applied to or installed on any grain binding harvester of ordinary construction, and it may be produced and applied at a very moderate expense. 120

What I claim as new is:

In combination with a harvester having 125 a grain table, a conveyor belt mounted along the table, and an inclined elevator belt aligned with the grain table and having its receiving end spaced from the delivery end of the conveyor belt, a frame consisting of 130

spaced rods having end portions disposed along the grain table and under the conveyor belt, said rods having upwardly inclined end portions which extend under the elevator belt, the rods bridging the space between the receiving end of the elevator belt and the delivery end of the conveyor belt, said rods being provided at the delivery end of the elevator belt with downwardly curved extremities, and a cover disposed over the rods under the grain table and the conveyor belt and under the elevator belt, said cover terminating at one end at the downwardly curved extremities of the rods and at its other end beyond the 15 other extremities of the rods and at this latter end curved upwardly, the portion of the cover disposed below the grain table and conveyor belt being provided with a plurality of openings. 20

In testimony whereof I affix my signature.
STEVE NOVAK.
